UNITED STATES PATENT OFFICE.

THOMAS D. LEMIEUX, OF CLEVELAND, OHIO.

CYLINDER-HEAD FOR SLEEVE-VALVE MOTORS.

1,091,359.

Specification of Letters Patent. Patented Mar. 24, 1914.

Application filed October 8, 1913. Serial No. 794,125.

To all whom it may concern:

Be it known that I, THOMAS D. LEMIEUX, a citizen of the United States, residing at Cleveland, in the county of Cuyahoga and State of Ohio, have invented certain new and useful Improvements in Cylinder-Heads for Sleeve-Valve Motors, of which the following is a specification, reference being had to the accompanying drawings.

10 This invention relates to new and useful improvements in sleeve-valve motors and more particularly to a cylinder head therefor and the primary object of the invention is to provide means in connection with the cylinder head to prevent the noise incident to the use of motors of this character.

A further object of the invention resides in providing means in connection with the cylinder head to permit explosive gases to pass therethrough and expand the packing rings circumscribing the same.

Still another object of the invention resides in providing a plurality of slots or channels in the bottom of the cylinder head which communicate with one of the grooves containing a packing ring, whereby the compression may pass through said slots or channels to cause said ring to expand in the operation of the motor.

30 A still further object of the invention resides in providing a device which is simple and durable in construction, inexpensive to manufacture and one which will be very efficient and useful in operation.

35 With these and other objects in view, the invention consists in the novel features of construction, combination and arrangement of parts as will be hereinafter referred to and more particularly pointed out in the specification and claim.

40 In the accompanying drawing forming a part of this application, Figure 1 is a fragmentary vertical section through a cylinder head embodying my improvements therein; and Fig. 2 is a bottom plan view thereof.

45 In describing my invention, I shall refer to the drawing in which similar reference characters designate corresponding parts throughout the several views and in which 50 1 indicates a cylinder head such as is used in connection with a well known type of sleeve-valve motor, the depending portion of said cylinder head being received in the upper portion of a sleeve-valve 2. Inasmuch as this sleeve-valve and head as shown, are

used in connection with a motor of a well known type, a detailed description of the construction thereof will not be here given. It will be stated here, however, that this cylinder head has a depending portion 60 which is designed somewhat hollow to form a water chamber 3 therein and the outer face of the depending portion of the head surrounding this water chamber is provided with annular grooves or channels 4, in which 65 are arranged the packing rings 5. These packing rings obviously contact with the inner wall of the sleeve-valve 2 as the latter is reciprocated and after constant use, become worn, thus permitting the loss of compression therethrough. When these rings 70 become worn, they are obviously loose in their grooves and as the sleeve-valve 2 is reciprocated, considerable noise occurs at the points at which these rings are located. 75

My invention primarily contemplates the provision of a means to remedy this difficulty and, to this end, the extreme lower portion of the cylinder head 1 which is increased in thickness and designed annular, 80 as shown at 6, is provided with a plurality of outwardly inclined channels or ports 7 which communicate with the adjacent groove 4 in the outer face of said cylinder head. In the drawing, I have shown but 85 four of such ports or channels, but it will be understood that as many of the same may be provided as are found desirable and it will be seen that as the explosions take place, the compression in the cylinder will 90 be passed through the channels or ports 7 to cause said rings 5 to expand. It will be seen, therefore, that these rings will expand when the motor is in operation, thus preventing a loss of compression at such points 95 and obviously eliminating the noise which ordinarily occurs at these points in motors which are not provided with such means as herein shown and described.

From the foregoing it will be seen that 100 I have provided a simple, inexpensive and efficient means for carrying out the objects of the invention, and while I have particularly described the elements best adapted to perform the functions set forth, it is obvious 105 that various changes in form, proportion and in the minor details of construction may be resorted to without departing from the spirit or sacrificing any of the principles of the invention. 110

Having thus described this invention, what is claimed is:—

In a motor of the class described, the combination with a cylinder head having a depending portion thereon, said depending portion being provided with a pair of spaced circumferential grooves disposed adjacent the lower end of said depending portion, the lowermost groove being of greater height than the upper groove, said depending portion of the head also having its lower peripheral edge provided with upwardly and outwardly inclined channels terminating at their outer ends in the lowermost circumferential groove, and packing rings

mounted in the grooves of said head; of a sleeve valve slidably engaged with the depending portion of said cylinder head, said channels in the head permitting compression in the cylinder to be directed to the one groove to permit the packing therein to expand and fit tightly against the inner periphery of the sleeve valve.

In testimony whereof I hereunto affix my signature in the presence of two witnesses. 25

THOMAS D. LEMIEUX.
